UNITED STATES PATENT OFFICE.

ERNST SCHLEGELMILCH, OF SUHL, PRUSSIA, GERMANY.

GUN-LOCK.

SPECIFICATION forming part of Letters Patent No. 356,378, dated January 18, 1887.

Application filed December 1, 1886. Serial No. 220,422. (No model.)

To all whom it may concern:

Be it known that I, ERNST SCHLEGELMILCH, a subject of the King of Prussia, and residing at Suhl, Kingdom of Prussia, German Empire, 5 have invented new and useful Improvements in Gun-Locks, whereof the following is a specification.

My invention relates to breech-loading guns having a barrel or barrels hinged to the breech-frame (so-called "breakdown" guns) and provided with locks, the hammer whereof acts from behind against the cartridge; and its object consists in rendering the lock more simple than those heretofore used with the said kind 15 of guns. For this purpose the hammer is made in one piece, with a straight stem, (corresponding to the cocking-rod of other locks of this kind,) and it is guided by means of the said stem in a hole or channel bored through the 20 portion of the breech-frame extending under the barrel. On the said stem is placed the mainspring, forming a spiral, and abutting against shoulders on the stem and in the guiding-channel; and in the hinge part of the barrel is formed a cam-surface adapted to act 25 against the hammer-stem and to push the hammer back when the barrel is tilted, the hammer being then caught by the sear engaging with a notch on the head of the hammer.

On the annexed sheet of drawings a portion 30 of a double-barreled gun provided with my improved lock is represented by Figure 1 in vertical section along the center line of the front barrel and with the parts in the position 35 after firing. Fig. 2 is a like view showing the barrels tilted for loading and the hammer in cocked position. Fig. 3 is a top view of the sears and the trigger-plate, and Fig. 4 a side view of a part to be mentioned hereinafter.

The hammer consists of the head *a*, having 40 the beak *g* and the notch or bent *a'*, and of the stem *b*. By means of the said stem and the bush *c* screwed thereon, the hammer is guided in the channel *l*, bored through the lower part 45 of the breech-frame *m*. Between the bush *c*, forming a shoulder, *c'*, and another shoulder, *h*, in the socket *l*, is inserted the spiral mainspring *d*. This spring tends to press the stem *b*, with its end, which may be provided with a 50 roller, against the cam-surface *e*, formed in the

hinge-part *n* of the barrel. *f* is the sear, having the nose *f'*.

When the barrels are turned down to the position shown in Fig. 2, the cam-surface *e*, in acting against the end of the stem *b*, pushes 55 the hammer back and compresses the spring *d*, whereupon the nose *f'* of the sear *f* engages with the notch *a'* of the hammer-head *a* and keeps the hammer in a cocked state. In like manner and simultaneously the hammer of 60 the other barrel (not shown in the drawings) is cocked. For facilitating the movement of the stem *b* a roller, *l*, Fig. 4, may be placed under the bush *c*. After the barrels have been loaded and returned to their normal position 65 and also relocked, the gun is ready for firing.

In order that subsequent to the discharge the beak *g* of the hammer, which penetrates into the bottom of the cartridge, may not hinder the barrels from being opened, the spring 70 *d* is fitted in an uncompressed state with some play between the shoulders *h* and *c'*. The hammer under these conditions recoils a little after the discharge, and the beak *g* is withdrawn from the path of the breech end of the 75 barrels.

In the gun represented by the drawings the barrels are locked in known manner by the bolt *g* catching into notches of the lugs *r* on the under side of the barrels, the lever *p*, 80 and an intermediate piece. (Not shown in the figures.) These parts, however, do not form any portion of my invention, and they may be varied in any suitable manner. Certain other parts requisite to complete the gun—such as the 85 cartridge-extractor, a trigger-locking device, and indicator-pins—have also been omitted in the drawings, as they are neither involved in the present invention.

I claim as my invention—

1. In a breakdown gun, the combination, 90 with a barrel carrying the cam-surface *e* and a breech-frame, *m*, having the channel *l*, with shoulder *h*, of a hammer consisting of the head *a* with notch *a'*, and the stem *b* with shoulder *c'*, 95 guided in the channel *l*, the mainspring *d*, inclosed between the shoulders *h* and *c'* and pressing the stem *b* against the cam-surface *e*, and the sear *f*, having the nose *f'* adapted to engage with the notch *a'* of the hammer-head, 100

substantially as and for the purpose described.

2. The combination, with a barrel having the cam-surface *e*, a breech-frame having the channel *l* with shoulder *h*, a hammer consisting of the head *a* and the stem *b* with bush *c*, and the mainspring *d*, of the roller *k*, placed under the bush *c*, substantially as and for the purpose specified.

In testimony whereof I have hereunto set my hand in the presence of two subscribing to witnesses.

ERNST SCHLEGELMILCH.
